UNITED STATES PATENT OFFICE

ERICK W. ERICKSON, OF ENUMCLAW, WASHINGTON

TIME CONTROL FOR RADIOS

Application filed August 17, 1931. Serial No. 557,439.

My invention relates to devices adapted to be inserted in the electric power circuit of a radio set, whereby said circuit may be automatically closed to energize the radio at a certain predetermined time.

The object of my invention is to provide a switch device which, normally open, will be closed by means of a clock. Other objects are, to provide a switch which will be closed by the turning of an alarm-winding key of a clock, when the said alarm is started by the clock; which may be quickly applied to an alarm clock, or removed therefrom; which is readily reversible to adapt it for a winding key which winds in a left- or a right-hand direction; which is cheap to make, easy to apply, and effective in use.

I attain these and other objects by the devices, and arrangements illustrated in the accompanying drawing, in which—

Fig. 1 is an elevation showing a radio power circuit with my improved time control in operative connection therewith; Fig. 2 is an elevation of a part of the rear side of an alarm clock, showing my improved switch in operative position thereon; Fig. 3 is a side elevation of the alarm winder key, with the key clamp applied thereto; Fig. 4 is an end elevation thereof; Fig. 5 is a longitudinal section of the switch drawn to an enlarged scale and adapted for use on a right-hand winding alarm key; Fig. 6 is a similar view of the key end thereof showing the switch lever reversed to adapt it to a left-hand winding alarm key; and Fig. 7 is a cross-section of my improved switch, taken on the line 11—11 in Fig. 5.

Similar numerals of reference refer to similar parts throughout the several views.

In modern radio sets 1 the power circuit is connected to the ordinary house electric-light circuit by means of a power cable 2. Also the radio set is provided with a suitable switch, not shown, to complete or break the power circuit as desired. It is, however, often desired to turn on the radio set at some definite time automatically and this is accomplished with my apparatus, by means of a branch circuit 15, inserted in series in the

main power circuit 2 of the radio set, and leading therefrom to the hereinafter described clock-operated switch, which may be positioned at any desired location.

Referring now to the drawing, it will be seen that the wire 15 extends to the clock switch. This clock switch comprises a container made of suitable insulating material, said container being made of two cylinders 21 and 22. The upper open end of the cylinder 21 is slightly tapered off and is adapted to fit in the correspondingly shaped open lower end of the cylinder 22. The cylinder 21 has an opening at its lower end adapted to admit the cable 15 of the branch circuit. The two wires of the cable 15 are secured to the ends of two long flat springs 23 and 24 respectively. These springs 23 and 24 are secured on the two sides of an insulator separator bar 25, which extends from the lower ends of the said springs upward about two-thirds of the length of the said cylinder 21. The said springs 23 and 24 may each have an offset, as at 26, to engage the inside of the wall of the cylinder 21, as shown.

The upper cylinder 22 is provided with a transverse square removable shaft 27, carrying a key clamp 28 at one end and secured in place in the cylinder 22 by means of a nut 29, at the other end. The key clamp 28 comprises two spring ears adapted to tightly grip the flat portion of the alarm-winder key 30, of the clock 31, between them. These ears are preferably turned out at their lower ends (Fig. 4), thereby permitting them to be freely slid over the key 30, when the device is applied to a clock. Also, in some cases, the alarm winder key is made in channel form with two shallow separated ears and, in such cases, the said out-turned ears of the clamp are compressed between the ears of the key. The said square shaft 27 passes through the hub or boss 32 of the switch lever. This switch lever lies within the cylinder 22 and is preferably made of insulating material and comprises the hub 32 and the tangential arm 33. The arm 33 extends out towards the lower end of the cylinder 22 and is adapted to lie outside of one or the other of the springs 23 or 24 and to contact therewith when the

two parts of the switch are assembled, as shown.

- It is evident that the shaft 27 may be inserted through the hub 32 to cause the axis 6 of the key clamp 28 to lie either parallel with the axis of the cylinders 21 and 22 (Fig. 2) or at right-angles thereto (Figs. 3 and 4). Also it is evident that the hub 32 of the switch lever may be turned over to bring the arm 33 10 above the axis of the cylinders (Fig. 5) or below the said axis (Fig. 6), thereby adapting the switch to be applied to either a right- or a left-hand winding key 30.
- A rubber or other suitable tube 34 may be 15 placed over the lower end of the cylinder 21 and the cable 15 to keep the end of the cylinder from sliding if the clock is on a highly polished surface, as a table, and to reinforce the cable 15 at that point.
- 20 When it is desired to set the apparatus, the alarm clock 31 is set to act at the desired time and the key 30 is given a slight winding turn (about a quarter turn is sufficient) and then the key clamp 28 of the switch is slipped 25 over the key 30 in such manner that the end of the cylinder 21 will engage the base on which the clock 31 rests, when the alarm key 30 turns under the action of its released spring.

- 30 Then the radio switch is again turned on. When the alarm is, later, released by the time mechanism in the clock, the end of the cylinder 21 moves until it comes in contact with the base on which the clock 31 rests and 35 stops further rotation of the switch cylinders with the key but permits the further slight rotation of the key 30 about the axis of the shaft 27, thereby turning the hub 32 and arm 33 to push the one spring 23 into contact with the other spring 24, or vice versa, as shown in dotted lines in Fig. 5, and, when these 40 springs 23 and 24 are thus brought into contact, the power circuit is completed through them and the radio is started.

45 Having described my invention, what I claim and desire to secure by Letters Patent, is:—

1. In a time controlled switch, the combination with a time-released spring-wound key; of an elongated container clamped thereon, having a wire entering and leaving the container; two spring separated terminals for the wire positioned within said container; and a rotatable lever arm within said container and connected to said key, and 50 adapted to engage one of said terminals to complete the circuit when the key is actuated and when the end of the elongated container is prevented from further rotation.
- 60 2. In a time controlled switch, the combination with a time-released spring-wound key; of an elongated container, having a wire entering and leaving the container; a lever arm pivotally mounted in one end of said container; a clamp attached to said lever arm

and adapted to be secured to said key to support one end of said container; and two separated spring terminals for the circuit positioned within said container and adapted to be engaged by said lever arm and to be 70 brought into contact with each other when said key is actuated and when the end of the elongated container is prevented from further rotation.

Signed at Tacoma, Washington, this 30 day 75 of March, 1931.

ERICK W. ERICKSON.
